Primary Examiner — Clint A Samuel(74) *Attorney, Agent, or Firm* — Rumit Ranjit Kanakia(57) **CLAIM**

The ornamental design for a Christmas tree light, as shown and described.

DESCRIPTION

FIG. 1 is a perspective view of a Christmas tree light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partial enlarged part of FIG. 1.

The broken lines encircling portions of the Christmas tree light that are illustrated in enlargement, form no part of the claimed design.

1 Claim, 9 Drawing Sheets(56)
